Primary Examiner — S. Bryan Reinholdt, Jr.*Assistant Examiner* — Ieisha N Price(74) *Attorney, Agent, or Firm* — Terry M. Sanks, Esq.; Beusse Sanks, PLLC(57) **CLAIM**

The ornamental design for a shackle, as shown and described.

DESCRIPTION

FIG. 1 is a front perspective view of the shackle;
FIG. 2 is a top view thereof;
FIG. 3 is a bottom view thereof;
FIG. 4 is a front view thereof; the back view being a mirror image thereto;
FIG. 5 is a left side view thereof;
FIG. 6 is a right side view thereof;
FIG. 7 is a front perspective view of the shackle thereof with the bolt removed for ease of illustration;
FIG. 8 is a top view thereof of FIG. 7;
FIG. 9 is a bottom view thereof of FIG. 7;
FIG. 10 is a front view thereof of FIG. 7; the back view being a mirror image thereto; and,
FIG. 11 is a left side view thereof of FIG. 7; the right side view being a mirror image thereto.
